United States Patent Office

Des. 186,959
Patented Dec. 29, 1959

186,959

MOTION PICTURE PROJECTOR

Dominic Anthony Saporito, Royal Oak, Frank Andrew Ilenin, Bloomfield Hills, and Frederick Hertzler, St. Clair Shores, Mich., assignors to Sylvania Electric Products Inc., New York, N.Y., a corporation of Delaware

Application May 19, 1959, Serial No. 55,969

Term of patent 7 years

(Cl. D61—1)

Des. 186,959

PAGE 2

Figure 1 is a side elevational view, somewhat in perspective, of a motion picture projector, showing our new design;

Figure 2 is a top plan view;

Figure 3 is a front elevational view, somewhat in perspective;

Figure 4 is a rear elevational view, somewhat in perspective; and

Figure 5 is an opposite side elevational view thereof.

We claim:

The ornamental design for a motion picture projector, substantially as shown.
